UNITED STATES PATENT OFFICE

2,536,424

RELEASABLE LOCK FOR GUIDE BUSHINGS

John C. Curtis, Claremont, N. H., assignor to Joy
Manufacturing Company, a corporation of
Pennsylvania

Application March 21, 1945, Serial No. 583,868

3 Claims. (Cl. 308—24)

1

This invention relates to fluid operated tools and more particularly to improvements in a hammer rock drill of the reciprocating piston type.

In fluid operated tools such as hammer rock drills, the motor cylinder contains a reciprocating hammer piston usually provided with an elongated reduced front extension or striking bar for delivering impact blows to the shank of the working implement. The front piston extension extends through a bore in the front cylinder head or buffer ring and some difficulty has been experienced in the adequate guiding of the piston extension. To overcome this difficulty, replaceable bearing sleeves or bushings have been supported within the front buffer ring for providing a bearing for the piston extension, and such bushings become worn and must be replaced at intervals. It is therefore desirable to provide means for securing the bushing in position in the front head and such securing means must be readily releasable to enable easy replacement of the bushing. It is also desirable to provide releasable securing means whereby the bushing may be readily locked in its guiding position and held not only against axial displacement but also against rotative movement.

It is accordingly an object of the present invention to provide improved means for securing the guide bushing for the front piston extension or striking bar of a hammer rock drill against both axial displacement and rotative movement. Another object is to provide improved means for guiding the front extension of the reciprocating hammer piston of a fluid operated tool. Still another object is to provide improved releasable means for locking the guide bushing in position in the front cylinder head or buffer ring, such means enabling easy locking of the bushing in guiding position and permitting ready release of the bushing for replacement purposes. These and other objects and advantages of the invention will, however, hereinafter more fully appear.

In the accompanying drawing there is shown for purposes of illustration one form which the invention may assume in practice.

In this drawing:

Fig. 1 is a fragmentary view in central longitudinal section through a hammer rock drill in which an illustrative embodiment of the invention is incorporated.

Fig. 2 is a cross-sectional view taken substantially on line 2—2 of Fig. 1.

Fig. 3 is a detail view of the improved locking element.

2

Fig. 4 is a perspective view of the replaceable bearing sleeve or guide bushing.

Fig. 5 is an enlarged fragmentary sectional view taken on the plane of Fig. 1, showing structural details of the invention.

In this illustrative construction there is shown a fluid operated tool, herein a hammer rock drill, in which the invention is incorporated. It will be evident that the invention may be associated with tools of other types.

The hammer rock drill comprises a motor cylinder 1 having a bore 2 in which a hammer piston 3 is reciprocable. The hammer piston has a head 4 fitting the cylinder bore and a reduced elongated front extension or striking bar 5 for delivering impact blows to the shank of a working implement 6, herein a conventional rock drill steel. Attached to the front end of the motor cylinder is a chuck housing 7 containing a chuck 8 for receiving and supporting the drill steel. The piston extension 5 extends through a bore in a front cylinder head 9, and pressed in the front head bore is a bearing sleeve or guide bushing 10 providing a bearing surface for the piston extension for guiding the latter during reciprocation of the piston. The front head 9 has a rearwardly located, inwardly directed annular flange 11 providing a forwardly facing shoulder 12 against which the rear end of the bushing abuts, and the flange 11 is cut away or notched at 13 so as to enable, when the drill is dismantled, the placing of a suitable instrument against the rear end of the bushing to permit driving out of the bushing from the head bore. The forward portion of the bushing is externally reduced at 14 and has a notch at 15 in the reduced portion. The front head 9 is recessed at 16 and internally annularly grooved at 17. When the bushing is driven in position in the front head bore, a locking ring or spring lock 18 is placed about the reduced front end of the bushing and snapped into position in the groove 17 with a bent end portion 19 received in the front head recess 16 in the manner shown. An end 20 of the spring lock is inserted in the notch 15 in the bushing. When the drill is assembled, the locking ring 18 serves to hold the guide bushing against forward axial displacement from the front head bore, and the end 20 received in the bushing notch 15 serves to hold the bushing against rotative movement in the head bore. When it is desired to replace the bushing, as in the event of wear, the drill may be dismantled and the locking ring pried or otherwise released from its locking position by springing the ring out of the groove 17.

and releasing the bent portion 19 from the recess 16. An instrument may then be inserted in one of the notches 13 against the rear end of the bushing to permit driving out of the bushing from the head bore.

It is accordingly evident that an improved guiding means is provided for the front extension of the reciprocable piston of a fluid operated tool. It will further be evident that by the provision of the improved releasable spring lock, the guide bushing may be readily locked in guiding position in the front motor head, and may also be readily released when desired. The improved bushing lock is simple and inexpensive in construction and is extremely compact, and due to its design may be associated with a standard type of hammer rock drill with a minimum of change. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a member having a bore forming an annular shoulder at one end and having an annular groove in its walls near its opposite end providing a shoulder opposed to said annular shoulder and a recess with which said groove communicates, a guide bushing received in said bore and adapted to guide a member to be guided, said bushing at one end engaging said annular shoulder, and a releasable lock for retaining said bushing in said bore with said one end thereof against said annular shoulder including an expansible split spring ring surrounding said bushing and seated in said groove, said ring engaging a surface on said bushing opposed to said groove-shoulder and having a bent portion at one end received in said recess and at said end interlocked with said bushing to hold the latter against substantial rotation in said bore, said ring being contractible to effect release thereof from said groove to permit axial release of said bushing from said bore, and said bent portion moving outwardly from said recess during such axial release of said bushing.

2. In combination, a member having a bore forming an annular shoulder at one end and having an annular groove in its walls near its opposite end providing a shoulder opposed to said

annular shoulder and a recess with which said groove communicates, a guide bushing received in said bore and adapted to guide a member to be guided, said bushing at one end engaging said annular shoulder and having a notch at its opposite end, and a releasable lock for retaining said bushing in said bore with said one end against said annular shoulder including an expansible split spring ring surrounding said bushing and seated in said groove and engaging a surface on said bushing opposed to said groove-shoulder, said ring having a bent portion at one end received in said recess and said end received in said notch to hold the bushing against substantial rotation in said bore, said ring being contractible to effect release thereof from said groove to permit axial release of said bushing from said bore, and said bent portion moving outwardly from said recess during such axial release of said bushing.

3. In combination, a member having a bore formed with an annular shoulder at one end and having an annular groove in its walls near its opposite end providing a shoulder opposed to said annular shoulder, a guide bushing received in said bore and adapted to guide a member to be guided, said bushing at one end engaging said annular shoulder and having a reduced portion at its opposite end providing a shoulder opposed to said groove-shoulder, and a releasable lock for retaining said bushing in said portion with said one end against said annular shoulder including an expansible split spring ring surrounding said bushing and seated in said groove and engaging said shoulder provided by said reduced portion, said ring having an end portion interlocked with said member and said bushing for holding said bushing against substantial rotation in said bore, and said ring being contractible to effect release thereof from said groove to permit axial release of said bushing from said bore, said ring moving out of interlocking relation with said member during such axial release of said bushing.
